K. J. E. HESSELMAN

VALVE CONTROLLING MEANS

Filed Sept. 9, 1925

FIG: 1.

FIG: 2.

Inventor,

Knut J. E. Hesselman,
By *Henry O. H. S.* atty.

UNITED STATES PATENT OFFICE.

KNUT JONAS ELIAS HESSELMAN, OF SALTSJO-STORANGEN, SWEDEN.

VALVE-CONTROLLING MEANS.

Application filed September 9, 1925. Serial No. 55,284.

To all whom it may concern:

Be it known that I, KNUT JONAS ELIAS HESSELMAN, a citizen of the Kingdom of Sweden, residing at Saltsjo-Storangen, Sweden, have invented new and useful Improvements in Valve-Controlling Means, of which the following is a specification.

This invention relates to improvements in valve controlling means.

In my copending application Serial No. 733,597, filed August 22, 1924, I have described and claimed a fluid pressure operated valve controlling device which comprises a plurality of independent annular flexible discs placed one above another so as to form a hollow column the individual discs of which engage each other loosely alternately at their inner and outer edges, said column being closed at its one end by a disc having a channel formed in it in communication with the interior of the column, said disc being formed integral with a member to guide the discs laterally and to carry means to hold the discs assembled in longitudinal direction, and loose means to close the end of the column opposite to said integral end disc.

According to the present invention the discs are formed without a permanent guiding member and instead thereof a loose guiding member is temporarily used to prevent the discs from lateral relative displacement while the discs are being assembled and until after the initial compression thereof has been applied thereto, whereupon the guiding member is withdrawn.

In the accompanying drawing two embodiments of the invention are illustrated—

Fig. 1 being a longitudinal section of one embodiment, and Fig. 2 a longitudinal section of the other embodiment.

Figs. 3 and 4 show longitudinal sections of modified types of flexible discs.

In the embodiment shown in Fig. 1 the valve casing 12 is formed with a passage 23 for supplying fuel under pressure. Furthermore, the casing 12 is provided with a plug 13 to close one end of the casing, said plug having a fuel outlet passage 14 extending therethrough, a valve seat 15 at the uppermost end of said passage and a fuel nozzle 16 at the lowermost end thereof. Resting on the valve seat 15 is a plate valve 19 formed centrally in the upper side of which is a recess 20. The plate valve 19 supports

a plurality of annular flexible discs 5 placed one above another so as to form a column having a central through-extending aperture, the diameter of said aperture being equal to that of the recess formed in the upper surface of the plate valve 19. The discs 5 are shown for convenience as constructed in accordance with Fig. 3 of the specification of my aforesaid application for patent, but may take other forms, if desired.

The discs are held in a suitably compressed state between the valve plate 19 and the threaded cover 24 of the valve casing. Said cover 24 is formed with a longitudinally extending passage 25 of the same diameter as that of the apertures of the discs 5. This passage 25 and the apertures of the discs 5 are adapted to receive a bolt 27, and the recess 20 in the upper surface of the plate valve 19 is adapted to receive the lower end of said bolt. The bolt 27 is provided at its top with a head 28 having any appropriate form of operating means, as a handle 29. Formed on the under side of the head 28 is a projection or key 30 to engage a corresponding slot formed in the top surface of the cover 24.

In assembling the structure just described the members 24 and 5 are disposed on the bolt 27, while the latter is held with the head 28 down, whereupon the plate valve 19 is placed on the end of the bolt so that said end will engage the recess 20 formed in the plate 19. The valve casing is thereupon placed over the members while held thus assembled, whereupon the cover 24 is screwed into the casing by means of the bolt 27, the projection 30 of which is in engagement with the slot in the top surface of the cover. This arrangement ensures that the cover cannot be screwed down into the casing 12 until after the members 19, 5 and 24 are held in proper relative position by the bolt 27, which position is maintained during the whole screwing down operation. By tightening the bolt 27 any initial compression desired may be given to the discs 5. The bolt 27 may then be removed, inasmuch as the said compression and the pressure exerted by the fuel will hold the discs assembled sufficiently to prevent any lateral displacement of the discs relatively to each other. The passage 25 of the cover 24 for the temporary reception of the bolt 27 will, after removal of the bolt, form a passage leading from the

atmosphere to the interior of the bellows as formed by the discs 5 and plate valve 19.

Fig. 2 illustrates a modification of the structure shown in Fig. 1 in order to facilitate the assembling. In this embodiment the cover 24 carries a sleeve 31, screwed thereon, having at its lower end an inward flange 32 adapted to support the valve plate 19 and the discs 5 resting thereon. The bolt 27 and its operating means are similar to those in Fig. 1, and also in this case the bolt is used for screwing down the cover 24 into the valve casing 12. In this embodiment the members 19, 5 and 24 may be more readily assembled and the bolt brought into engagement therewith to prevent said members from relative lateral displacement during their insertion into the casing 12, as well as during the screwing down of the cover, which last-mentioned operation is effected in the manner herein described in connection with Fig. 1.

While in Figs. 1 and 2 the flexible discs are shown as engaging each other alternately at their inner and outer edges, it is to be noted that they may contact only at their inner or outer edges. In such cases the discs may be so designed as is shown in Figs. 3 and 4.

It is to be noted, of course, that while the invention is described and illustrated as applied to a fuel valve, it may equally well be utilized for many other purposes without departing from the principle of the invention.

What I claim is:

1. In a fluid pressure operated valve controlling device, a casing adapted to be internally subjected to the fluid pressure, a set of annular flexible discs adapted to be inserted into said casing so as to loosely engage each other to form a longitudinally flexible hollow column, an imperforate independent end piece at one end of said column, an apertured independent end piece at the opposite end of said column, and means adapted to transiently engage said discs and said end pieces to prevent said members from being displaced laterally relatively to each other during the actions of assembling the device.

2. In a fluid pressure operated valve controlling device, a casing adapted to be internally subjected to the fluid pressure, a set of annular flexible discs adapted to be inserted into said casing so as to loosely engage each other to form a longitudinally flexible hollow column, an imperforate independent end piece at one end of said column having a recess formed in its surface adjacent the column, an apertured independent end piece at the opposite end of said column, and a bolt adapted to transiently engage the apertures of the disc and the said lastmentioned end piece and the

recess of the said firstmentioned end piece to snugly fit therein.

3. In a fluid pressure operated valve controlling device, a casing adapted to be internally subjected to the fluid pressure, a set of annular flexible discs adapted to be inserted into said casing so as to loosely engage each other to form a longitudinally flexible hollow column, an imperforate independent end piece at one end of said column having a recess formed in its surface adjacent the column, an apertured independent end piece at the opposite end of said column, and a bolt adapted to transiently engage the apertures of the disc and the recess of the said first mentioned end piece to snugly fit therein said bolt having means to facilitate operation thereof.

4. In a fluid pressure operated valve controlling device, a casing adapted to be internally subjected to the fluid pressure, having a valve seat at one end and screw threaded opening at its other end, a set of annular flexible discs adapted to be inserted into said casing so as to loosely engage each other to form a longitudinally flexible hollow column, an imperforate end piece at one end of said column having a recess in its surface adjacent the column, a screw-threaded apertured cover adapted to be screwed down into said casing to maintain the said column therein, a bolt adapted to be transiently inserted into the apertures of said discs and said cover to engage the said recess with its free end, a handle on said bolt, and means to effect an engagement between said bolt and said cover to enable the cover to be rotated by rotating the bolt.

5. In a fluid pressure operated valve controlling device, a casing adapted to be internally subjected to the fluid pressure having a valve seat at one end and a screw threaded opening at its other end, a set of annular flexible discs adapted to be inserted into said casing so as to loosely engage each other to form a longitudinally flexible hollow column, an imperforate end piece at one end of said column having a recess in its surface adjacent the column, a screw-threaded apertured cover adapted to be screwed down into said casing to maintain the said column therein, a bolt adapted to be transiently inserted into the apertures of said discs and said cover to engage the said recess with its free end, a handle on said bolt, means to effect an engagement between said bolt and said threaded cover to enable the cover to be rotated by means of the bolt, and means attached to said threaded cover to support the imperforate end piece and the annular discs resting thereon.

In testimony whereof I have signed my name.

KNUT JONAS ELIAS HESSELMAN.
